UNITED STATES PATENT OFFICE.

CHARLES N. PYE, OF STOUGHTON, MASSACHUSETTS.

LAST.

SPECIFICATION forming part of Letters Patent No. 737,770, dated September 1, 1903.

Application filed June 25, 1902. Serial No. 118,120. (No model.)

To all whom it may concern:

Be it known that I, CHARLES N. PYE, a citizen of the United States, and a resident of Stoughton, county of Norfolk, State of Massachusetts, have invented an Improvement in Lasts, of which the following description, in connection with the accompanying drawings, is a specification, like letters on the drawings representing like parts.

10 This invention has for its object the production of novel, simple, and effective means for strengthening and increasing the pressure-resisting qualities of the heel part of a last at a small cost and in a convenient manner.

15 Lasts are subjected to but slight strain at their fore parts; but substantially all crushing, twisting, or distorting strains to which a last is subjected at different times are concentrated upon or directed to the heel part 20 and tend to so injure the last as to render it worthless. Various devices have been made to reduce in greater or less degree or to obviate such damage to the last and comprise thimbles or socket-pieces of different kinds, 25 metallic comb-plates, anvil-heels, &c.; but in many instances they increase the cost of the last, are heavy, and very inconvenient to apply.

In my present invention I have provided 30 means for distributing over the heel part of the last the various crushing or twisting strains to which it may be subjected and for resisting such strains adequately and effectively without injury to the last, while at the 35 same time adding but little to the weight of the last or its cost of production and with no increase in the inconvenience or cost of applying the invention to the last.

As will hereinafter appear, the resistance 40 to vertical or crushing pressure upon the heel part of the last acts longitudinally and transversely of the heel part.

The various novel features of my invention and its practical advantages will be hereinafter described, and particularly pointed out in the following claims.

Figure 1 is a side elevation and part section of a last having one embodiment of my invention applied thereto. Fig. 2 is a transverse section on the line xx , Fig. 1. Fig. 3

is a detached perspective view of the pressure-resisting and distributing member shown in Fig. 1.

I have chosen for convenience to illustrate my invention in connection with a block-last; 55 but the invention is not restricted thereto, as any other desired kind or construction of last may be used.

Referring to Figs. 1 and 2, the heel portion B' of the last B is provided with a vertical hole b, bored into the solid material of the heel portion from its flattened head b^x , and a longitudinal and substantially semicircular socket b' is formed in the heel portion intersecting the thimble-hole b. The socket is 60 made in a convenient and rapid manner by a circular cutter of the requisite diameter and thickness in a manner well known to those skilled in the art. As shown in the drawings, the thimble-hole b is made, and 65 preferably so, of greater depth than the depth of the socket b' in order to receive the thimble or spindle socket of requisite length.

One embodiment of the pressure resisting and distributing member is shown separately 75 in Fig. 3, and it comprises a flat and preferably elongated head a, its outline conforming substantially to the top b^x of the heel portion of the last, its squared end a^x abutting against the transverse shoulder b^2 of the 80 last, Fig. 1, said head having a hole a', forming a continuation of the bore of the tubular thimble or spindle socket a². This thimble, closed at its lower end, as at a³, Fig. 2, is of sufficient length to receive the supporting- 85 spindle of the jack or other device which sustains the last when in use, and the thimble depends from the head a.

On the under side of the head I have shown a segmental web a⁴, extended longitudinally 90 of the head along its median line and connecting the head and the thimble, as shown, said head, thimble, and web being made of metal and preferably by casting in a suitable mold. The web is of sufficient thickness to 95 fit snugly in the socket b' in the heel portion of the last, with its curved face a⁵ resting on or seated upon the correspondingly-curved bottom of the socket b'.

From the foregoing description and the 100

drawings it will be manifest that vertical pressure or crushing strains upon the heel portion of the last when in use will be resisted by the head *a*, the closed end of the 5 thimble *a*², and the curved face of the web *a*⁴, the parts named resting upon the solid material of which the last is made, so that the pressure is distributed over a wide area and well equalized over the entire heel portion. The head *a* also protects the top of the heel portion from crushing and is in one sense an impact member. By the general distribution of the strains through the heel portion the wood, of which lasts are commonly made, is protected from splitting due to unequal and localized strains.

In order to retain the pressure distributing and resisting member in place in the last, I have herein shown two strong pins *d*, preferably made of steel, which are inserted in holes drilled transversely through the heel portion of the last, behind and in front of the thimble, as herein shown, and passing through holes *a*⁶ in the web *a*⁴. Not only do 25 the pins act as retaining devices, but they also serve to distribute the strains transversely to the heel portion and additionally resist pressure applied to the head *a*.

It will be observed that the tools requisite to 30 adapt a last for the application of my novel pressure resisting and distributing member are a drill or auger for the thimble-socket *b*, a smaller drill for the holes for the pins *d*, and a circular saw or milling-cutter of the required 35 site diameter and width of cutting-face.

I have herein shown one practical embodiment of my invention, and I have not attempted to show or describe the various modifications or changes thereof which might be 40 made by those skilled in the art without departing from the spirit and scope of my invention.

Having described my invention, what I claim, and desire to secure by Letters Patent, 45 is—

1. A last having its heel provided with a metallic pressure resisting and distributing member comprising an elongated head, and an integral segmental web inserted and wholly 50 inclosed in and extended longitudinally of the heel of the last and having its curved face resting upon the solid material thereof, the head resting upon and being supported by the top of the heel.

55 2. A last having its heel provided with a metallic pressure resisting and distributing member comprising an elongated head, and a substantially semicircular, integral web inserted in and extended longitudinally of the 60 heel of the last and having its curved face seated directly upon the solid material there-

of, the head resting upon and being supported by the top of the heel.

3. A last having its heel provided with a metallic pressure resisting and distributing member 65 comprising an elongated head, and an integral substantially semicircular web inserted and wholly inclosed in and extended longitudinally of the heel of the last and having its curved face resting upon the solid material thereof, the head resting upon and being supported by the top of the heel, and a retaining device for said member, extended transversely through the heel and in engagement with the web.

4. A last having its heel portion provided 70 with a vertical thimble, a flat, elongated head integral therewith and resting upon the top of the heel, and a segmental web joining the head and thimble and extended longitudinally of the heel portion at opposite sides of the thimble, the solid material of the heel portion contacting with and supporting the curved face of the web.

5. A last having its heel portion provided 75 with a vertical thimble closed at its inner end, a flat, elongated head integral therewith and resting upon the top of the heel, and a segmental web joining the head and thimble on 80 opposite sides of the latter and extended longitudinally of the heel portion, the solid material of the latter contacting with and supporting the curved face of the web, and a retaining device extended transversely through 85 the web and the adjacent material of the heel portion.

6. A last having its heel portion provided 90 with a vertical thimble-hole and a longitudinal, intersecting semicircular socket, and a pressure resisting and distributing member 95 inserted in the heel portion, said member comprising a thimble, an attached flat head to rest upon the top of the heel portion, and a longitudinal segmental web to enter the socket and having its curved face seated 100 upon the correspondingly-curved bottom of the socket.

7. As a new article of manufacture, a pressure resisting and distributing member for lasts, consisting of a head, an integral thimble, and a substantially semicircular web connecting the opposite sides of the thimble and the head and extended longitudinally 105 of the latter.

In testimony whereof I have signed my 110 name to this specification in the presence of two subscribing witnesses.

CHARLES N. PYE.
